UNITED STATES PATENT OFFICE.

CURTIS J. ROTHERMEL, OF PHILADELPHIA, PENNSYLVANIA.

BALE TIE.

Application filed May 19, 1922. Serial No. 562,051.

To all whom it may concern:

Be it known that I, CURTIS J. ROTHERMEL, a citizen of the United States, residing at Philadelphia, county of Philadelphia, State 5 of Pennsylvania, have invented a new and useful Bale Tie, of which the following is a specification.

In the usual manner of securing metal bands around packages or containers such as 10 boxes and bales, there is ordinarily a waste of band material especially when the ends of the tie are looped around the ends of the fastener and in many types of fasteners only one holding point is provided.

15 It is the purpose of my present invention to devise a novel construction of a bale tie wherein the metal band is provided near its free ends with slots extending longitudinally of the band and a fastener of novel 20 construction is employed formed from a metal band to provide a head and prongs which will pass through registering apertures and after such prongs are bent over so that the fastener will lie flat on the box 25 or bale around which it is secured.

Other novel features of construction and advantage will hereinafter more fully appear in the detailed description.

For the purpose of illustrating my invention, I have shown in the accompanying drawings typical embodiments thereof which are at present preferred by me, since these embodiments will be found in practice to give satisfactory and reliable results. It is, however, to 35 be understood that the various instrumentalities of which my invention consists can be variously arranged and organized and that my invention is not limited to the precise arrangement and organization of these instrumentalities as herein shown and described.

Figure 1 represents, in perspective, a bale in conjunction with which a bale tie, embodying my invention, is employed.

45 Figure 2 represents, in perspective, the free ends of the band, with the fastener about to be connected therewith.

Figure 3 represents, in perspective, a bale tie in fastened position.

50 Figure 4 represents, in perspective, a rear view of the bale tie.

Figure 5 represents, in perspective and in detached position, the fastener employed.

Figure 6 represents a section on line 55 6—6 of Figure 3.

Figure 7 represents, in perspective, the

free ends of a band in conjunction with another type of fastener, embodying my invention.

Figure 8 represents, in perspective, the 60 parts seen in Figure 7 in assembled position.

Figure 9 represents, in perspective and in detached position, an embodiment of fastener seen in Figures 7 and 8.

Similar numerals of reference indicate corresponding parts.

Referring to the drawings.

1 designates a package which may be of any desired nature such as, for example, a 70 box or a bale, a bale being shown in the drawing. 2 designates a metal band which is provided in any desired manner with the slots 3 which extend longitudinally of the band. These slots can be either punched 75 out or formed by expanding the metal when the band is manufactured or they can be made by a suitable tool at any desired place or places after the band has been drawn up around the packages. 4 designates a fastener, embodying my invention, which is formed from a sheet metal band having the rear wall of the body portion 5, the band then being directed inwardly, as at 6, and the free ends being deflected at substantially right angles from the portion 6, as indicated at 7.

85 In some cases in practice, I have found it advantageous to have the free edges at the front end of the prongs 7 inclined, as indicated at 8, in order that the fasteners may be more readily secured in position. After the band has been tightened around the package to bring apertures or slots 3 at the free ends of the band into register, the 90 prongs 7 are passed therethrough and then bent over with a suitable tool so that they 95 lie flat against the band and the two bands are secured tightly together. It will of course be understood that one or more of 100 these fasteners may be employed.

105 In practice, the fastener is inserted through an aperture near one end of the band and the band is then tightened by means of a suitable tool around the package and brought into position for the prongs 7 to pass through an aperture 3. If the outer face of the prongs 7 is inclined it is somewhat easier to tighten the band into position as it will more readily slip over the 110 prongs 7. Attention is directed to the fact that I employ an elongated aperture or slot

which extends in the direction of the length of the band, so that the two bands are rigidly secured together and the free ends cannot work sideways. The body portion 5 can be on the inner or outer faces of the bands, a suitable tool being employed to press down the prongs 7 into position.

The size of the slots and fasteners will vary in accordance with the size of the band 10 and the amount of tension which is to be placed on a band.

In accordance with my present invention there is no waste of band material as the band can always be cut off at the proper 15 length. The fasteners can be readily and quickly inserted into position, as all that it is necessary to do is to pass the prongs through registering apertures and bend them over with a suitable tool. It will be seen that the width of the strip employed to 20 make the fastener is preferably substantially the same as the width of the band and the free ends of the prongs extend in proximity to the edges of the metal band so that 25 a very rigid fastening device is provided, which will prevent any relative longitudinal or lateral movement of the free ends of band after it has been secured in position around the bale, box or other container. Both the 30 band and the fastener are preferably made of sheet metal. Both of the prongs of the fastener pass through the same registering aperture at the free ends of the band.

It will now be apparent that I have devised 35 a new and useful bale tie which embodies the features of advantage enumerated as desirable in the statement of the invention and the above description, and while I have, in the present instance, shown and described embodiments thereof which will give in practice satisfactory and reliable results, it is to be understood that these embodiments are susceptible of modification in

various particulars without departing from the spirit or scope of the invention or sacrificing any of its advantages. 45

Having thus described my invention, what I claim as new and desire to secure by Letters Patent, is:—

1. The combination with a band having 50 slots at its free ends extending in the direction of the length of the band and of greater length than width, of a fastener formed from a flat metal strip and having 55 prongs of less width than the length of said slots and adapted to be inserted through two registering slots to substantially fill such slots and to be bent over the juxtaposed portion of a band to extend laterally thereof and prevent relative longitudinal or lateral movement of said ends, and said band being deflected to form a head of double 60 thickness of the strip and of substantially the same width as the band, and said prongs when bent over extending into proximity to 65 the sides of the band.

2. The combination with a band having slots at its free ends extending in the direction of the length of the band and of greater length than width, of a fastener 70 formed from a sheet metal band deflected upon itself near its central portion to form a double thickness and thereby a head of substantially the same width as the width of the slotted band and provided with flat 75 forwardly extending prongs adapted to pass through two registering slots and substantially fill them to prevent relative longitudinal or lateral movement of said ends, the free ends of said prongs being cut away 80 at an angle to facilitate their insertion in registering slots.

CURTIS J. ROTHERMEL.
